GILBERT H. CLEMENS, OF NEW YORK, N. Y.

Letters Patent No. 83,930, dated November 10, 1868.

IMPROVED ELASTIC CALK FOR BOOTS AND SHOES.

The Schedule referred to in these Letters Patent and making part of the same.

To all whom it may concern:

Be it known that I, GILBERT H. CLEMENS, of the city, county, and State of New York, have invented a new and useful article of manufacture, to be applied to the heels of either boots or shoes, for the purpose of preventing persons, when wearing them, from slipping when walking upon the ice or snow; and I do declare that the following is a full and exact description thereof, references being made to the accompanying drawings by figures and letters.

The prominent feature in my invention is in constructing an ice-heel-calk, of elastic material, which I propose shall be made of soft rubber, being the most suitable substance now in use.

The said ice-heel-calk is intended to be applied to the heels of either boots or shoes, and moulded or formed to fit the size and shape of any heel, and, when expanded sufficiently, can be readily placed upon the heel, and, by the elastic compression of the rubber, adhere firmly to its place, and, to a certain extent, produce a vacuum, causing the same to remain very firm upon the heel, but, for additional security against a possibility of the said heel-calk being thrown off the heel when in use, I have attached a band to either side of the said calk, which passes around the instep of either boot or shoe.

The bottom surface of the elastic calk has a series of unbroken curved corrugations, but there may be square or oblong projections substituted in place of the curved corrugations. The object in forming the corrugations in the manner shown, in the place of making them checked, as they are applied to the bottoms of rubber shoes, is to produce a greater adhesion to the ice or snow by the flexible corrugations, when pressed upon the ice or snow by the weight of the person wearing them, effectually excluding the air, and forming a vacuum which will prevent the possibility of the foot slipping.

For additional security against the person slipping when walking upon ice or snow, I have inserted, from the inside of the elastic calk, a metal calk, which is concave on the bottom surface, and when the weight of the person wearing the calk presses upon one of the calks, the elastic surface will be compressed sufficiently to force the metal calk into the ice, and thereby hold the foot securely against slipping.

These metal calks can be removed from the elastic calk, and be replaced by others, or may be dispensed

with entirely, or may be constructed in any other suitable form, or more than one may be used.

The elastic calk may also be secured to the heel of a boot or shoe by a conical-headed screw, passing through the said disk, and screwed into the heel of the boot or shoe.

The following references to the letters and figures marked upon the drawing will further explain my invention:

Figure 1 is a side elevation of a portion of the boot or shoe, with the elastic calk attached to the heel, and the red lines show the band attached to said calk, and passing over the instep.

Figure 2 is an end elevation of a boot or shoe, with the elastic calk attached.

Figure 3 is a side elevation; with the calk detached from the heel.

Figure 4 is a bottom view of the elastic calk, showing the series of corrugations.

A represents a boot, with the elastic calk B applied to it. C represents the metal disk, provided with a flange at its top face, while the lower end is made concave.

What I claim, and desire to secure by Letters Patent, is—

1. A rubber heel-calk, moulded or made to fit on to a boot or shoe-heel, in combination with the metallic disk C in the bottom of the same, all as and for the purpose specified.

2. A rubber heel-calk, moulded or made to fit on to a boot or shoe-heel, in combination with a band or bands, strap or straps, to pass around the instep of the boot or shoe, for the purpose of holding the heel-calk on the heel of the same, all as shown and described, and for the purpose set forth.

3. A rubber heel-calk, moulded or made to fit on to a boot or shoe-heel, the bottom of which is made with a series of corrugations, constructed substantially as shown and described, and for the purpose specified.

4. The combination of a rubber heel-calk, made to fit on the heel of a boot or shoe, with the strap or straps to hold it thereon, the metallic disk C, and the corrugations on the bottom of the calk, all substantially as shown and described, and for the purpose specified.

Witnesses: GILBERT H. CLEMENS.
